DEVICE FOR FEEDING ACOUSTIC FILMS AT CONSTANT SPEED.

Application filed July 9, 1924. Serial No. 725,070.

For regulation of the speed at which film is fed forward in cinematographic apparatuses and the like, it has been proposed before, as is well known, to use a flywheel 5 which drives a roller on which the film is running.

One condition which is necessary in order that a constant speed of motion of the film by means of a regulating mechanism of such 10 nature may be attained, independently of smaller variations of speed in the mechanism serving to operate the film, is that the film be prevented from sliding on the said roller, and that the mass of the flywheel be 15 so large that the flywheel, during temporary smaller variations of the driving power, may maintain the speed of motion of all the rotary parts of the apparatus, and retard the driving mechanism, when the latter tends 20 to run at higher speed.

The object of the present invention is to provide film-feeding mechanism by which the said condition is satisfied. For this purpose, the flywheel and the roller coupled 25 thereto are driven by the film, and means are provided which engage the leading portion of the film—i. e., the portion of the film located between the film-feeding roller and the roller coupled to the flywheel—and exert 30 thereon a resilient pressure which causes the film to pass in a bight between said two rollers. The extent of the bight increases and decreases automatically with the variation of the speed of the feeding roller and 35 its rotating means, and will thereby prevent slight temporary variations of the speed of the latter, from being transmitted to the portion of the film passing the sound-recording or sound-reproducing point. Besides, 40 said bight has the effect that sudden or permanent variations of the speed of the driving motor are only gradually transmitted to the flywheel and to the arriving portion of the film, so that the tension in the latter will 45 nowhere be exposed to any corresponding sudden increase, but will increase gradually, and rupture of the film will be prevented.

The further details of the invention will become apparent from the construction of 50 the same illustrated in the accompanying drawing,

Fig. 1 showing, diagrammatically in side elevation, a feeding and regulating mechanism, and,

Fig. 2 a detail of the same, on a larger scale in front elevation.

Figs. 3 and 4 show, in diagrammatic side elevation, a feeding device according to Fig. 1 combined with sound-recording and reproducing apparatus, respectively. 60

Referring to the drawing, 1 is a film passing around a roller 2 having a rough surface, the film being moved, in the direction indicated by the arrow P in Fig. 1, by a driving mechanism which is here shown as 65 comprising a film feeding wheel 3 of known kind. The feeding wheel 3 is driven for instance by an electromotor 3' (Fig. 1) in such a manner that it moves at approximately uniform speed. Owing to the friction 70 against the surface of the roller 2, the film 1 will rotate the latter and, thereby, drive a flywheel 4 connected to the roller and serving in known manner to maintain the rotary 75 speed of the roller 2 uniform.

In order to prevent the film from sliding on the roller 2, the former is pressed against the surface of the roller by means of rubber covered rolls 5 which are controlled by a spring or springs 7, each of the said rolls 80 running partly on the surface of the roller and partly on the film 1, Fig. 2, where the rolls 5 for the sake of clearness are shown lifted somewhat up from the film. The rolls 5 are journalled at the ends of pivoted arms 6 to which the spring or springs 7 are attached. 85

The portion of the film 1 which is located between the roller 2 and the feeding wheel 3 passes in a bight over a roller 8, which is 90 journalled on the end of a pivoted arm 9 actuated by a spring 11, in such a manner that the roller 8 exerts a resilient pressure on the film. 95

When for some reason or other the rotary speed of the feeding wheel 3 is temporarily increased, the consequence will be that more film per second must run to the feeding wheel 3 than before, whereby the length of the said bight will be reduced, and the arm 100 105 9 with the roller 8 will then swing out in the direction indicated by the arrow p in Figure 1. The increased supply of film to the feeding wheel 3 due to the increase of speed will therefore, if the increase of speed occurs only temporarily, be effected by a shortening of the said bight, without any appreciable variation of the tensile stress of the film.

If the speed of the feeding wheel 3 is reduced, the arm 9 with the roller 8 will 110 swing in such a manner that the length of the film bight will be increased correspond-

ing to the decreased supply of film to the feeding wheel. When the speed of the feeding wheel 3 once more becomes normal, then the arm 9 will gradually swing back into 5 the position shown in Figure 1, the bight being gradually shortened down again to its normal length. By suitable selection of the size of the flywheel 4, the result will be attained that this flywheel maintains the 10 speed of motion of the film practically constant during the time passing from the occurrence of a speed reduction of a certain duration, until the film bight is again reduced to its normal length. By giving the 15 bight of film a suitable size, the result may be attained that all variations of the speed of the driving mechanism, within certain limits which may be presumed not to be exceeded during normal conditions, will be 20 entirely equalized in the manner here described.

In case of a sudden great increase or a permanent increase of the speed of the driving mechanism, the bight of film will be 25 shortened considerably, and the arm 9 with the roller 8 will move considerably in the direction indicated by the arrow *p*. Thereby, however, the pressure of the roller 8 against the film will be increased gradually 30 by the spring 11 and, consequently, the said spring will offer a gradually increasing resistance against shortening of the film bight. In consequence, the tension of the film bight and, hence, the tensile stress in 35 the portion of the film between the roller 2 and the feeding wheel 3 will gradually become greater, and will gradually increase the speed of the flywheel, until there has been established a new state of equilibrium 40 between the driving power and the resistance against motion of the rotary parts corresponding to the new speed at which the driving mechanism adjusts itself.

Sudden and permanent increases of speed 45 are in this manner transmitted quite gradually to the flywheel and to the portion of the film running towards the roller 2, without such speed increments causing any sudden and impermissible increases of the tension of the film.

The size of the flywheel 4 is independent 55 of the mass and motive energy of the other rotary parts, and it depends, aside from the frictional resistances occurring in the sound record gate 10 concerned and in the bearings of the rotary parts, and from the increase of tension of the spring 7 caused by a certain rotation in the direction *p*, only upon the duration of the speed variations 60 to be equalized, the mass of the flywheel having to be selected in such a manner that the flywheel, within the time interval in which a speed variation to be compensated 65 may occur, must be able to maintain the speed of the roller 2 practically constant.

Instead of a roller 8 use may be made of a loop, arm or other suitable member resting resiliently against the film and doing the same service as the roller 8.

In the apparatus illustrated in Figs. 3 70 and 4, the film 1 is moved by the feeding roller 3, which is an ordinary pin-roller, and by a second pin-roller 20 coupled in any suitable manner to the pin-roller 3 or to the driving mechanism in order that the 75 two rollers 20 and 3 may rotate synchronously. 25 in Fig. 4 indicates guide rollers for the film.

According to Fig. 3, sound waves are 80 graphically recorded on the film 1 by means of an oscillating mirror 30, which is supported by a wire loop 31 and is caused to oscillate in known manner in conformity with the phonic currents that pass through the said loop due to the action of an electro- 85 magnet 32 which is energized from a current source 33. 34 indicates a beam of light reflected by the mirror 30 towards a lens 36, which concentrates the said light on the film, thus causing in known manner the recording of the sounds on the film. The light 34 is produced by a light source (not shown) arranged in suitable manner in the chamber 35 of the apparatus.

According to Fig. 4, the sound waves recorded on the film 1 are reproduced in known manner by illuminating the film from a light source 40, a condensing lens 41 being inserted between the said light source and the film. By means of a lens 100 42, an image of the recorded graphic representations is formed across a light-sensitive cell 43, for instance a selenium cell, inserted in a reproducing circuit 44.

Having now particularly described and 105 ascertained the nature of our said invention and in what manner the same is to be performed, we declare that what we claim is:

1. A constant-speed film-feeding mechanism, comprising a feeding roller; means for continuously rotating the same; a flywheel; a roller coupled to the flywheel and driven by the passage of the film thereover; and means to compensate variations in the motion of the film due to irregularities in the 115 rotary motion of the feeding roller.

2. A constant-speed film-feeding mechanism, comprising a feeding roller; means for continuously rotating the same; a flywheel; a roller coupled to the flywheel and driven 120 by friction action of the film passing thereover; and means to compensate variations in the motion of the film due to irregularities in the rotary motion of the feeding roller.

3. A constant-speed film-feeding mechanism comprising a feeding roller; means for continuously rotating the same; a flywheel; a roller coupled to the flywheel and driven 125 by friction action of the film passing there-

over; a pivoted lever; a roller journalled on one end thereof; and a spring acting to force the last-named roller against the portion of the film located between the feeding roller and the flywheel roller with a resilient pressure which causes the film to pass in a bight in its travel from the flywheel roller onward to the feeding roller, the extent of the bight increasing and decreasing in accordance with the variations in the speed of the feed roller and its rotating means.

4. A constant-speed film-feeding mechanism, comprising a feeding roller; means for continuously rotating the same; a flywheel; a roller coupled to the flywheel and driven by friction action of the film passing thereover; and an adjustable member engaging the portion of the film located between the feeding roller and the flywheel roller and exerting on such portion a resilient pressure which causes the film to pass in a bight over said member in its travel from the flywheel roller onward to the feeding roller, the extent of the bight increasing and decreasing in accordance with the variations in the speed of the feed roller and its rotating means.

5. A constant-speed film-feeding mechanism, comprising a feeding roller; means for continuously rotating the same; a flywheel; a roller coupled to the flywheel and driven by friction action of the film passing thereover; and an adjustable member embodying a lever, a roller journalled on one

end thereof, and means acting to force the last-named roller against the portion of the film located between the feeding roller and the flywheel roller with a resilient pressure which causes the film to pass in a bight in its travel from the flywheel roller onward to the feeding roller, the extent of the bight increasing and decreasing in accordance with the variations in the speed of the feed roller and its rotating means.

6. A constant-speed film-feeding mechanism, comprising a feeding roller; means for continuously rotating the same; a flywheel; a roller coupled to said flywheel and driven by friction action of the film passing thereover; a pivoted lever; a roller journalled on one end of said lever; a spring acting upon the lever to force the last-named roller against the film and thus cause the latter to pass in a bight from the driven roller onward to the driving roller; two rubber-covered rollers partly overlying the film and partly overlying the driven roller; and means adapted to force said rubber-covered rollers against said driven roller and film, so as to secure between the film and the driven roller a considerable friction effect which prevents the film from sliding on the driven roller.

In testimony whereof they affix their signatures.

ARNOLD POULSEN.
